The ornamental design for a battery-powered, extensible-retractable vibrator, as shown and described.

DESCRIPTION

FIG. 1 is a perspective view of a battery-powered, extensible-retractable vibrator, showing my design;

FIG. 2 is a top plan view thereof;

FIG. 3 is a bottom plan view, thereof;

FIG. 4 is a cross-sectional view thereof, taken along line 4—4 of FIG. 1, with the vibrator in a retracted position, and enclosed by its top cover; and,

FIG. 5 is an exploded view of the device in its operational position, with the vibrator in an extended position, and the top cover removed.
